(57) **CLAIM**

The ornamental design for a battery, as shown and described.

DESCRIPTION

FIG. 1 is a perspective view of a battery;

FIG. 2 is a side of the battery shown in FIG. 1;

FIG. 3 is another side view of the battery shown in FIG. 1;

FIG. 4 is a rear view of the battery shown in FIG. 1;

FIG. 5 is front view of the battery shown in FIG. 1;

FIG. 6 is a bottom view of the battery shown in FIG. 1;

FIG. 7 is a top view of the battery shown in FIG. 1;

FIG. 8 is a perspective view of a battery;

FIG. 9 is a side of the battery shown in FIG. 8;

FIG. 10 is another side view of the battery shown in FIG. 8;

FIG. 11 is a rear view of the battery shown in FIG. 8;

FIG. 12 is front view of the battery shown in FIG. 8; and,

FIG. 13 is a top view of the battery shown in FIG. 8.

The broken line showing is included for the purpose of illustration and forms no part of the claimed design.
